UNITED STATES PATENT OFFICE.

MARSELIUS T. ASH, OF BROOKLYN, NEW YORK, ASSIGNOR TO WILLIAM H. OWEN, OF NEW YORK, N. Y.

CARTON-FILLER.

1,035,534.

Specification of Letters Patent.

Patented Oct. 14, 1913.

Application filed February 7, 1912. Serial No. 676,046.

To all whom it may concern:

Be it known that I, MARSELIUS T. ASH, a citizen of the United States, residing at Brooklyn, in the county of Kings and State of New York, have invented new and useful improvements in Carton-Fillers, of which the following is a specification.

My invention relates to machines for automatically measuring the contents and filling cartons.

The object of my invention is to produce a machine for filling cartons with a predetermined quantity of granular or flaky substances from a reservoir or bin containing the same.

A further object thereof is to produce a plurality of measuring buckets carried on an endless carrier each of which are adapted to register and project at one end into a carton carried on an endless conveyer and to deposit in said cartons a predetermined quantity of granular or flaky substance which has been deposited into each bucket in its passage beneath the spout of a bin or reservoir.

Another object of my invention is to provide each of such filling buckets with an inner adjustable wall which may be regulated to control the capacity thereof according to the density of the substance being handled and thus determine the quantity deposited into each carton.

Still another object thereof is to produce means for conveying the empty cartons to the operator to be inserted in position upon the conveyer, and means for maintaining the properly spaced position upon said conveyer.

A still further object of my invention is to produce an attachment for agitating the cartons after they have been filled in their passage on the conveyer to settle and compact the contents, and for other purposes to be hereinafter more fully set forth.

To these ends my invention includes the combinations and arrangement of component parts to be hereinafter described and more particularly pointed out in the claims.

In the accompanying drawings, in which like reference characters indicate similar parts, Figure 1 is a side view of my invention; Fig. 2 is an end view thereof; Fig. 3 is a view of the opposite end; Fig. 4 is a plan view thereof, and Fig. 5 is a detail sectional view of one of my filling buckets.

Fig. 6 is a transverse side view of the same, partly in cross-section; Fig. 7 is a top plan view of one of said filling buckets taken on the lines 7—7 of Fig. 5 showing a pivoted lever for operating the false wall thereof; Fig. 8 is a similar view showing the means for fastening the buckets upon the endless chains; Fig. 9 is a detail plan view of my device for feeding empty cartons upon the conveyer, and Fig. 10 is a detail view of my means for agitating the cartons to settle the contents therein.

My invention includes, generally, a plurality of filling buckets carried on an endless chain, each of which are open at the top to receive a charge of material from a reservoir or bin, and each being provided with a pivoted bottom or gate carried on an arm adapted to be automatically opened to dump the contents thereof, and with an adjustable wall adapted to be regulated from without to control the cubic capacity thereof; an endless conveyer beneath said chain of filling buckets and placed on a relatively retreating plane; said conveyer being timed in its travel to coincide with said chain, and adapted to carry a plurality of cartons which in their initial position thereon telescope said buckets, but which in their passage become disengaged therefrom, after being filled by the retreating relative angle of the conveyer to the bucket carrier; an endless traveler provided with a plurality of spacing fingers adapted to retain the cartons in proper position on the conveyer; an agitator beneath said carton conveyer adapted to settle and compact the contents of the cartons; and a feeding and delivering device for conveying the empty cartons adjacent to their point of entry upon the endless conveyer, said conveyer and delivery being timed to accord with the travel of the filling conveyer.

Referring now to the drawings, 1 and 1^a indicate a pair of endless sprocket chains carried on the sprockets 2 and 2^a and 3 and 3^a rigidly mounted on the vertical shafts 4 and 5. The shaft 5 is an idler while shaft 4 is provided with the beveled gear 6 meshed with the driving gear 7 coupled with a suitable driving power. Suitably secured upon said sprocket chains 1 and 1^a as by brackets 1^b are carried a plurality of hopper shaped or downwardly tapered buckets 8, the upper edges of which are substantially rec-

tangular, and the adjacent edges of which contact with each other, and the upper longitudinal edges are provided with an extension flange 9 adapted to embrace the mouth 5 of the hopper or chute 10 from which they are filled in their passage beneath same, to prevent the spill of materials. As shown more particularly in Fig. 5 of the drawings, the walls of each of said buckets 8 are 10 tapered downwardly, and each is provided with an inner or false wall 8' on one side, which is hinged at its upper end at 8" and provided with an arm 8"" projecting through an orifice in the back wall of the 15 bucket to contact with an adjustable bar 12 beneath the filling chute 10, which may be regulated to press said false wall 8' inwardly a predetermined distance to adjust the cubic capacity of each bucket when being filled. It will be apparent that when 20 the buckets in their travel pass out of contact with said adjustable bar, said false wall will drop back in normal position and lie upon the outer wall of the bucket. Each of said 25 buckets is open at the top, but adjacent to the bottom is provided with a gate 11 by which the contents are held therein and automatically dumped into the cartons. In the 30 present embodiment of my invention, said gate is carried on a lever 11', which is fulcrumed intermediate of its ends on the side wall of the bucket at 11" with the free end of the lever projecting beyond the wall to be engaged by a beveled bar A to raise or 35 open the gate at the proper time and discharge the contents of the buckets. As shown in the drawings, the gate 11 enters the bucket through a slot in one wall, the edges of which are provided with out-turned 40 lips a and b to guide it in position.

Beneath the string of buckets, thus described, I provide a conveyer B comprising an endless belt 12' carried on horizontally disposed drums 13 and 13', one of which is 45 suitably belted with the driving shaft 25 by the belt 26 and timed to travel coincident with the sprocket chains 1 and 1'. As shown in the drawings the outer drum 13' is on a lower plane than drum 13 by which 50 arrangement the belt slants away from the horizontally disposed sprocket chains and buckets above same to automatically disengage the cartons carried on the belt as they reach the end thereof.

55 The empty cartons C are delivered adjacent to the end of the conveyer B and the drum 13 by means hereinafter described, and as the buckets charged with the contents turn about the sprockets on the shaft 4, a 60 carton is telescoped upon the lower end of each bucket and deposited upon the belt 12' and together travel to the opposite end of the conveyer. The lever 11' is tripped and the gate 11 of each bucket is opened automatically when the carton is adjusted on the

belt and the contents of the bucket deposited therein.

Owing to the fluffy character of the granular contents, it is necessary to settle or compact same within the carton. For this purpose I provide a longitudinal table 14 supported on pivoted adjustable links 14' between the upper and lower portions of the belt 12' adapted to support the upper portion of the conveyer on which the cartons travel. The height of said table may be adjusted by shifting the angles of said links. Beneath this table 14, is mounted a longitudinal shaft 15, suitably connected with power for revolving same, intermediate the 75 ends of which it is provided with cranks or eccentrics 15' on which are mounted the pitmen 15" extending upwardly. These are bent to avoid the lower portion of the belt 12' and support the longitudinal board 16 beneath the table 14, and by which the conveyer belt may be vibrated or agitated vertically. It will be appreciated that the violence of this action may be regulated by relative height of the table 14 as adjusted on the link supports, as the thrust thereof may be thereby adjusted to be accommodated to the condition of the contents of the cartons.

The vibration of the belt and cartons thus described would tend to displace the cartons 95 on the conveyer, and to overcome this action, I provide an endless traveler 17 comprising a sprocket chain 17' carried on sprocket wheels 17^a and 17^b mounted on the shafts 4 and 5, which is provided with a plurality of pivoted fingers properly spaced to engage each of the cartons and hold them in spaced position on the conveyer and beneath the filling buckets.

The empty cartons are delivered to the receiving end of the conveyer by the belts 18 and 19 to be inserted thereon by the operator. Said belts are carried on the drums 20' which are driven by the belts 26. The empty cartons are then placed on the table 20 beneath the filling buckets as they successively approach the end of the conveyer by the pivoted arm 21 operated by the disk 21' and eccentric pin 21" mounted on the shaft 4 and thus timed to accord with the travel of the filling buckets 8. Adjacent to the outer or free end of said arm 21 is secured a cross bar 22 on the ends of which are secured the uprights 22' projecting upwardly on either side of the ends of the delivery belts 18 and 19. On the outer or upper ends of each of the uprights is attached the brackets 23 projecting inwardly and adapted to alternately shift the cartons from the ends of the delivery belts to the 110 table 20 as they oscillate with the arm 21, when the carton may be readily telescoped upon the end of the filling bucket just coming into position therefor.

The construction and operation of my in- 115

vention may be readily understood from the foregoing description and by reference to the accompanying drawings, and it will be appreciated that the parts and combinations thereof may be varied or modified within a wide range from the specific exemplification shown without departing from the spirit and scope of my invention.

Having thus described my invention, 10 what I claim as new, and desire to be secured by Letters Patent, is—

1. In a carton filler, the combination with a traveling conveyer for carrying a plurality of cartons, of a plurality of traveling buckets adapted to be successively charged with contents for said cartons, an adjustable inner wall in each bucket, means for successively adjusting the position of said walls while the buckets are being charged, 20 and means for successively discharging the contents thereof into said cartons, substantially as described.

2. In a carton filler, the combination with a traveling conveyer for carrying a plurality of cartons, of a plurality of traveling buckets adapted to be successively charged with contents for said cartons, an adjustable inner wall in each bucket, means for successively adjusting the position of said walls 30 while the buckets are being charged, a gate carried on a pivoted arm for normally closing each bucket, an inclined bar for tripping said arm and opening the gate to discharge the contents of the buckets into the 35 cartons, substantially as described.

3. In a carton filler, the combination with an endless chain carried on sprocket wheels, means for driving said wheels, an endless belt for conveying cartons mounted on 40 drums beneath said chain and on a relatively inclined plane from said endless chain, means for driving said belt timed with said chain, a plurality of automatically dumping buckets carried on said

chain, a bin for charging said buckets with 45 contents, an endless chain timed with said first mentioned chain and belt intermediate of the said chain and belt provided with a plurality of pivoted fingers, an adjustable bar for regulating the cubic capacity 50 of each bucket while being charged with contents from said bin, a tripping bar for dumping the contents of the buckets while in registering relation with the cartons on the belt, a vertically adjustable support for 55 said endless conveyer, and a reciprocating plunger for vibrating said conveyer and cartons to compact the contents of the cartons, substantially as described.

4. In a carton filler, the combination with 60 a traveling conveyer for carrying a plurality of cartons, and means for filling said cartons, of conveyers for delivering empty cartons adjacent to said traveling conveyer, an oscillating arm for shifting the empty 65 cartons from said delivery conveyers into position for adjustment on said traveling conveyer, and an eccentric timed with the action of the filling means for operating said oscillating arm, substantially as de- 70 scribed.

5. In a carton filler, the combination with 75 a traveling carrier for carrying a plurality of cartons, of a plurality of traveling buckets adapted to be successively charged with contents for said cartons, an adjustable inner wall hinged at the top of each bucket, a lever for adjusting the position of said walls while the buckets are being charged, adjustable means for operating said lever 80 for positioning the inner walls, and means for successively discharging the contents of the buckets into the cartons, substantially as described.
